Primary Examiner — Clare E Heflin(74) *Attorney, Agent, or Firm* — Perkins Coie LLP(57) **CLAIM**

The ornamental design for a color changing circular light, as shown and described.

DESCRIPTION

FIG. 1 is a perspective view of a color changing circular light showing my design, as viewed from the top and front. FIG. 2 is a top plan view thereof.

FIG. 3 is a bottom plan view thereof.

FIG. 4 is a front profile view thereof.

FIG. 5 is a back profile view thereof.

FIG. 6 is a first side profile view thereof; and,

FIG. 7 is a second side profile view thereof.

The details shown in broken lines illustrate features that form no part of the claimed design.
